UNITED STATES PATENT OFFICE.

ROBERT G. C. BOA, OF HERKIMER, NEW YORK, ASSIGNOR TO REMINGTON ACCOUNTING MACHINE CORPORATION, OF NEW YORK, N. Y., A CORPORATION OF NEW YORK.

CALCULATING MACHINE

Application filed December 23, 1922. Serial No. 608,681.

To all whom it may concern:

Be it known that I, ROBERT G. C. Boa, citizen of the United States, and resident of Herkimer, in the county of Herkimer and State of New York, have invented certain new and useful Improvements in Calculating Machines, of which the following is a specification.

This invention relates to calculating machines and especially to combined typewriting and calculating machines which contain clearance proving mechanism.

An object of the invention is to provide for use in accounting machines of clearance proving mechanism capable of operating under conditions which do not allow other known forms of clearance proving mechanism to operate in such machines. Another object is to enable such machines to be provided with clearance proving mechanism of especially simple construction.

The invention consists in certain features of construction and combinations and arrangements of parts, all of which will be fully set forth herein and particularly pointed out in the claims.

Information that will enable any person skilled in the art to construct a machine embodying the invention is to be derived from Patent No. 1,270,471 granted June 25, 1918 to assignee of John C. Wahl, and from the following description and accompanying drawings, although many parts of the machine are not shown in these drawings.

In the accompanying drawings of which there are three sheets:

Figure 1 is a front elevation of mechanism comprised in a Remington accounting machine that embodies the invention, only fragments of some and vertical sections of some of the parts being shown;

Figure 2, a front elevation of some of the same mechanism shown in operation;

Figure 3, a right side and sectional elevation of a fragment of the machine;

Figure 4, a perspective of parts represented also in Figs. 1 and 2; and

Figure 5, a plan of a fragment of the top plate and some of the mechanism within the cross totalizer which the machine includes.

Figures 3, 4 and 5 are on a larger scale than Figures 1 and 2.

Similar reference numerals designate like parts in different views.

The drawings represent the invention in a form in which it is embodied in combined typewriting and calculating machines, such as are known as Remington-Wahl cross-footing or Remington accounting machines. The construction and operation of such machines, not including clearance proving mechanism, is explained in the above mentioned Patent No. 1,270,471, to which reference is made for a description of any mechanism which these drawings do not show and which Remington accounting machines include, or any mechanism which is particularly referred to and not fully illustrated herein. It will be understood that the invention claimed may be adapted and applied to different forms of calculating machines.

The machine includes a cross-totalizer and at least one column totalizer or dummy, but may include several column totalizers or dummies. The column totalizer 1 is the same as the well known Wahl column totalizer or vertical totalizer contained in Remington accounting machines, except that it has on it a trippet such for instance as the cam plate 2 (Figs. 1 and 3) which is rigidly attached to the casing or frame of the totalizer at the top and close to the right side of the frame. This cam plate is formed on the arm 3, which the top plate of the totalizer partly covers and which is integral with the cross bar 4, which extends across the casing under and close to the top plate and fits tightly at its ends in dove-tailed recesses cut in the side plates of the casing. The cross bar proper is part of the frame or casing of the common Wahl totalizer. A dummy consists merely of the framework of a totalizer, no computing mechanism being contained in it. If the trippet were attached to a dummy as it is to totalizer 1 and the dummy were to be substituted for this totalizer, the invention herein set forth would not be affected. But the invention depends on a totalizer which may be a cross-totalizer and is partly embodied in the calculating mechanism of the totalizer.

The bar 5 is part of the stationary framework of the Wahl mechanism, this bar being a casting which is fast on the frame of the typewriter. The plates 6 and 7 and the block 8 (Figs. 1 and 3) are parts of the framework of the cross-footing mechanism.

Plate 6 is attached by screws at its upper end to the right end of bar 5, plate 7 is attached to plate 6 and to part 9 of the framework, and block 8 which is a casting fits between 6 and is fastened to plates 6 and 7. The fastenings include screws 10 (Fig. 3) passing through ears on block 8 and thence into plate 7 and include other screws passing through the plate 6 and thence into ears on 10 the block at its right end.

A suitable number of column totalizers or dummies or both, including the totalizer 1, are mounted on the decimal carriage or truck 11 which is supported at the middle 15 of the machine by rolls 12 and 13, the latter mounted on part 14 of bracket 15 fast on bar 5. The truck is connected with and partly supported at its ends by the typewriter carriage, and travels with it towards 20 the left and towards the right. The totalizer is secured on the truck by well known means which is described in said Wahl patent and which allows the totalizer to be set at different places on the truck. When this 25 totalizer travels step by step over the main master wheel 16 of the machine to each decimal position in order, gears of the totalizer successively engage with that wheel as explained in the Wahl patent, so that 30 motion may be imparted to them by the master wheel actuated from the numeral keys. A dummy put in place of this vertical totalizer would travel step by step over the master wheel but would not touch it or 35 prevent it from being turned by the numeral keys and mechanism actuated thereby.

The truck 17 is the cross-footing carriage which is mounted to travel along block 8 on the ball bearings 18, and to said truck is 40 connected the long tension coil spring 19 that runs over a pulley and draws the truck towards the right when it is allowed to move in that direction.

The totalizer 20 (Figs. 1, 3 and 5) is the 45 cross footing jumping totalizer mounted on truck 17 and arranged to be operated by the cross-footing actuator comprising the master wheel 21.

In the operation of the machine, the truck 50 17, which normally stands at the right end of its path of travel, is picked up at times by any vertical totalizer or dummy by means of the hook 22, pivoted at 23 on bracket 24 fast on the truck 17. This hook engages a 55 lug 25 (Fig. 3), such a lug being formed on the right side plate of each vertical totalizer and dummy. As a number is written and calculated, truck 17 is drawn toward the left until the last carrying wheel 26 is 60 engaged with master wheel 21, when the totalizer is in the units position, and at the next step of the carriage hook 22 is disconnected from the lug, whereupon the cross-footing truck is drawn to the right by 65 spring 19, the adjustable stop bar 27 on said

truck striking lever 28 as the totalizer reaches normal position and forcing the lever against frame plate 6. This lever is pivoted at 29 to an ear on plate 6, and spring 30 tends to swing the lever to the left. 70 Slide link 31, through which lever 28 passes, is movable by this lever a short distance to the left or right in guides formed in the framework. When this link or slide is moved it rocks bell crank 32, pivoted at 33 75 to the framework and supporting at its left end the blocking device 34 pivoted to the bell crank at 35 and hanging close to the front end of fixed stud 36 having the longitudinal slot 37 in its under side. The construction is such that when lever 28 is in the position shown in Fig. 1, to which position it is turned by spring 30, the lower end of blocking plate 34 is above slot 37, and when the lever is in contact with plate 6, 80 the lower end of plate 34 is about even with the under side of stud 36. The swinging or angular movement of plate 34 on its pivot 35 is controlled through pin 38 by link 39 pivoted at 40 to the depending arm of swinging frame 41, pivoted on rock shaft 42, which is mounted in the framework. The frame 41 has roller 43 on the arm which extends to the left from shaft 42, which roller 85 is normally held in an upper position by means of the spring 44 but is adapted to be depressed, when a vertical totalizer or dummy is over the master wheel, by the track or rail 45 mounted in the casing of said totalizer or dummy (Figs. 1 and 3). The 90 whole construction is such that when there is no vertical totalizer or dummy over the main master wheel then plate 34 has been swung so far to the left as not to be able to cover slot 37 in post 36; but when a 95 vertical totalizer or dummy passes over the master wheel then said plate is swung to the right far enough to enable it to cover the slot when the plate is in its lowest position. This is well known locking 100 mechanism used in the Remington accounting machine and described in said Wahl patent. It will be perceived that it is so constructed that plate 34 cannot close the end of slot 37, except (1) when a vertical totalizer or dummy is over the main master wheel, and (2) when lever 28 is in its right-hand position, so that it requires a combination of two conditions to cause said plate 105 to block up said slot.

Each of the numeral keys when it is struck actuates or tends to actuate a device sometimes called a fan, which is adapted to engage the universal bar 46, consisting of a roller mounted in arms fast on the 110 universal rock shaft 47, on which the arm 48 also is fast. The universal bar when it is moved by the fan is swung towards the front of the machine so that shaft 47 is 115 rocked and a backward angular movement 120 125 130

is imparted to arm 48. This arm always moves into slot 37, except when, under the above mentioned combination of conditions, the slot is blocked by plate 34. Then shaft 5 47, universal bar 46, the fans, keys and other devices all are locked, and the machine cannot be operated thereafter until plate 34 shall have been withdrawn from in front of slot 37. The described lock is a well 10 known part of the Remington accounting machine, and it is convenient to use it in connection with my improved clearance proving mechanism, but it is to be understood that other means for locking an essential 15 part of the machine might be substituted for it.

In the column which totalizer 1 locates on a work sheet is to be written the result of a calculation which has been performed 20 in the cross totalizer, which then may show, for instance, the balance of an account, such as is commonly recorded on a sheet of a loose-leaf ledger. The machine can be set especially to adapt it to perform over and 25 over again some regular program of writing and calculation. An instance of such a program with which users of Remington accounting machines are familiar, is that of making daily entries on ledger sheets which 30 consist of leaves of a loose-leaf account book. According to this program the items written in one day are contained in four columns called "Debtor," "Creditor," "Balance," and "Old balance" or "Pick-up balance," said columns occurring on the paper 35 in the order named. In this program totalizer 1 would correspond to the third or "balance" column, a totalizer or dummy 49 (indicated by dotted lines) on the right of 40 1, to the "old balance" column, a totalizer or dummy 50 (indicated by dotted lines) on the left of 1, to the "creditor" column and another totalizer or dummy on the left of 50 to the first or "debtor" column. In 45 using the machine when a ledger sheet is put into it around the platen, the first operation is to write the old or pick-up balance in the fourth column. Usually this is written on the same line as the balance 50 which had been written in the third column (located by totalizer 1) at the next preceding operation on that particular ledger sheet. The operator, therefore, when the 55 paper is put into the machine, turns the platen to bring the last written line to the writing line and in the fourth column copies the balance seen just to the left of it in the third column. The paper is then line spaced and the carriage drawn back to begin a 60 new line of writing. The debtor item is then written in the first column, and the creditor item in the second column, and the resulting balance is then written in the third column located by totalizer 1 and this is the 65 end of the program. If there is more than

one debtor or creditor item to be entered, the paper is line spaced and the second item written under the first, but in every case the writing of the new balance in the third column is the last operation on that particular 70 sheet at that particular time. This sheet is then removed from the machine, another sheet is inserted and the program is repeated. In Fig. 1 the parts are shown ready for the writing of the digit of lowest order in 75 the third column, and the next key-stroke, to write said digit will end the program. This last key-stroke will cause the carriage to step one space to the left, and the cross-totalizer as it steps from units position to be 80 freed and allowed to snap back to its extreme right-hand position, or at least as far as dummy or totalizer 49 will allow it to go. When the next ledger sheet is put into the machine the carriage is already in position to allow the operator to copy in the pick-up balance for that sheet. 85

In the program described the calculation of the new balance is effected on the cross-totalizer 20, and this is accomplished by 90 causing the pick-up balance written in the fourth column to be added into the cross-totalizer, and the debtor item or items written in the first column to be also added in the cross-totalizer, and the creditor item or 95 items written in the second column to be subtracted in the cross-totalizer. At this time the cross-totalizer will show the new balance, and if the cross-totalizer is set for subtraction when the new balance is being 100 copied in the third column the copying of said new balance, if correctly done, will bring said cross-totalizer to zero. In this program, therefore, the cross-totalizer should always stand at zero when it is freed 105 for its jump to the right by the next key-stroke made when the parts are in the position shown in Fig. 1.

In order to cause the numbers to be automatically added and subtracted as described, subtraction cam plates such as are used in Remington accounting machines, and described in said Wahl patent, are placed on totalizer 1 and totalizer or dummy 50, but such a cam plate is not put on totalizer or dummy 49 or on the totalizer or dummy that locates the first or debtor column. It will be observed that as far as carrying out this program is concerned dummies could be used to locate all of the columns if preferred, but it is sometimes useful to preserve the grand total of all debtor items and of all creditor items and the first two columns are, therefore, frequently defined by totalizers rather than by dummies. 115 In some instances totalizers are used to locate the third and fourth columns, as the totals indicated at the end of the day can sometimes be used in checking up the work. 120

I have provided clearance proving mech- 125

- anism with means for bringing it into operation automatically by the last key stroke in the program, this being the point in the program at which the cross-totalizer should always be clear. In the present instance said clearance proving mechanism is brought into operation by the next step of the carriage from the position indicated in Fig. 1, this position being units position and this 10 step being the last in the clearing operation. At this same step the hook 22 will be released from the totalizer 1 and the cross-totalizer will jump back to the right impelled by its spring 19.
- 15 A bracket preferably made in one piece from sheet metal and comprising the flat base 51, upright part 52, top 53 and front 54, is secured on the top of casting 5 by screws that pass through the base 51 and into the casting. The screw 55 is one of these and the other (not shown) is on the left of bracket 15. Bracket 51-54 has in the base and upright parts an opening 56 through which bracket 15 passes, so that 20 base 51 extends behind and on both sides of bracket 15 and upright 52 extends over and on both sides of it. The pin 57, supported at its ends by upright 52 and front 54 of the bracket just described serves as a pivot 25 for an angular lever having a front leftward extending arm 58 and a rear arm 59 that extends downward and backward and through opening 60 in the upright part 52 of the bracket, the sheet metal of which this 30 angular lever is made being bent as shown and the lever bearing on pivot pin 57 at points spaced widely apart. Pin 57 is shown provided with a head and shoulder held in contact respectively with the backs 35 of upright 52 and front 54 of the bracket by a nut 61, this angular lever being confined between upright 52 and spacing sleeve 62 on pin 57 next to the front 54 of the bracket. Roller 63 on and at the left end 40 of arm 58 of the angular lever is normally in the path of travel of the trippet or cam plate 2, the construction and arrangement of parts being such that when totalizer 1 is in the position shown in Figs. 1 and 3 45 50 roller 63 rests on the flat top or dwell of the cam plate, the main master wheel then engaging the units carrying wheel of the totalizer; and when not on the cam 2, said roller occupies a lower position.
- 55 To arm 59 of the angular lever is connected the link 64 which extends therefrom nearly to the right side of the machine and is guided near its right end in an opening in an ear 65 of a sheet metal bracket 66, 60 which is bent as shown in Figs. 1, 2 and 4 and has in it two holes 67. That part of this bracket which contains these holes lies flat against frame plate 6 and the screws 68 that attach plate 6 to bar 5 pass through 65 these holes and secure the bracket also in place. Link 64 is connected at its right end to the upper end of the upstanding arm 70 of a latch 69 which is pivoted to bracket 66 on stud 71. When cam plate 2 passes under roller 63 it raises the roller and link 70 64 is drawn to the left and turns latch 69 on its pivotal axis from its normal position shown in Fig. 4 to the position shown in Figs. 1 and 2. As the cam plate moves from under the roller 63, latch 69, link 64, and the 75 angular lever comprising arms 58 and 59, are restored to their normal positions by a spring 72 attached to arm 70 of the latch and to a stud 73 fixed in bracket 66.
- When latch 69 is in its normal position 80 (shown in Fig. 4) it acts on a lever 74 pivotally mounted on a stud 75 fast on a lug 76 of bracket 66, the upper arm 77 of this lever extending nearly to the top of the bracket and the lower arm 78 being bent 85 as shown (see Fig. 4) and extending below and in front of the upper end of lever 28. A stud 79, affixed to and extending backward from arm 80 of latch 69, makes contact with edge 81 of projection 82 formed on arm 77 90 and keeps nose 83 of arm 77 in contact with the right end of bracket 66. As edge 81 then slopes a little to the left from its upper to its lower end spring 72 tends to force stud 79 down and said stud exerts a camming or wedging action to force projection 82 and the upper end of lever 74 towards the right so that arm 77 is held tight between the stud 79 and the end of the bracket 66. Spring 84, connected to arm 77 at its 100 upper end and to stud 85 fixed in bracket 66, is stretched when lever 74 is held in its normal position shown in Fig. 4. This lever at its lower end has a lug 86 which extends across the left edge of lever 28. 105 When lever 74 is free to be operated by its spring 84, the lug 86 forces the lever 28 to the position shown in Fig. 1 where said lever 28 operates the key lock as hereinbefore explained. A finger piece 87 formed on lever 110 74 at its lower end and overlapping the right face of frame plate 6 can be used to restore the lever 74 from its locking position shown in Fig. 1 to its normal position shown in Fig. 4. 115
- The action of lever 74 is also affected by another latch now to be described. This latch or lever, hereinafter called a latchlever, is pivotally mounted on the stud 88 affixed to ear 89 of bracket 66 and has arms 120 90 and 91. Arm 90 and block 92 projecting from the front face of the arm are fast together. Block 93 projecting from the front face of extension 94 of this arm is fast on the extension, and arm 91 is fast on blocks 125 92 and 93 at their front ends, block 92 forming a bearing which fits on stud 88. Obviously the construction of the latchlever could be more or less modified. The rearwardly bent lug 95 on arm 90 at its right end passes 130

under projection 82 of lever 74 and when both that lever and the latchlever are in their normal positions lug 95 is in the re-entrant angle formed by edges 96 and 97 of 5 the projection and in contact with edge 96, where it is held by a spring 98 attached to arm 90 of the latchlever and to a stud 99 fast on bracket 66. In this normal position of the latchlever, the lug 95 acting on 10 edge 97 is adapted to prevent the lever 74 from moving to its locking position, even if said lever 74 is freed from latch 69. The normal position of the latchlever is such that the downwardly extending nose 100 at 15 the left end of arm 91, which is bent forward at the left of bracket 93, is over and but a little above the highest portion 201 of the top plate of cross totalizer 20 when that totalizer is over master wheel 21, that 20 being the portion of said plate on which the scale showing letter space distances is usually put.

In the cross totalizer 20 (Figs. 3 and 5) each carrying wheel 26 meshes with an idler pinion 101 which meshes with a pinion 102 on the right side of the corresponding dial 103. Each of the pinions 102 has one short tooth 104 which, when the dial 103 stands at zero, occupies the position shown in Fig. 30. An arbor or rocking device 105 extends through the totalizer and at its ends has trunnions 106 which are pivoted in the side plates of the totalizer. This rocking device is in the form of a comb, also called 35 a feeler, comprising a series of feeler fingers 107. I have not fully illustrated this feeler comb because it is a well known construction, an instance of it being shown for example in Patent No. 1,311,710 dated July 40 29, 1919. The construction is such that if all of the wheels of the totalizer stand at zero then the fingers 107 can occupy the forward positions shown in Fig. 3, but if any one of said wheels does not stand at zero 45 then said wheel will have a full length tooth thereon in front of a finger 107 and said rocking device will be forced to occupy a position in the rear of that shown in the drawing.

50 The lever 108, pivotally mounted on stud 109 within the totalizer casing and close to the right side plate 110 to which the stud is affixed, extends on the right of and is connected to the feeler finger which is nearest 55 to that side plate, the lever having in it the slot 111 and the finger having affixed to it the pin 112 which fits loosely in this slot. This lever is normally kept by the light spring 113 in contact with a stop, for instance the shaft 116 of latch 117, and then the feeler fingers are held just out of reach of the long teeth of pinions 102. The rear arm of the lever passes through slot 118 60 in part 210 of the top plate of the totalizer, and when the lever is in its normal posi-

tion the top 119 of that arm is in alignment with nose 100 of the above described latchlever, as indicated by dotted lines in Fig. 3.

If an operator, following the above explained program correctly copies the new 70 balance in the third column of a ledger sheet, and simultaneously clears the cross-totalizer, the clearance proving mechanism does not require any attention from him. Whenever totalizer 1 approaches units position, in which it is shown in Fig. 1, trippet or cam plate 2 acts on and raises roller 63, rocking latch 69 to its inoperative position; and as totalizer 1 steps to units position end 119 of lever 108 is brought close to or into 75 contact with nose 100 of latchlever 90-91. While the vertical totalizer stands in that position, as the units figure of the number is about to be written, latch 69 is so held that pin 79 is above the upper end of edge 80 81 of projection 82 on lever 74 so that if this lever were not kept in its normal position by other means besides this latch the lever would be moved by spring 84 to the locking position shown in Fig. 2. But lug 90 95 of the latchlever, in contact with edge 97 of the projection, prevents spring 84 from so moving lever 74. On the next step of totalizer 1 and the cross totalizer, instantly following the writing of the units figure, 95 end 119 of lever 108 is drawn against nose 100, and if the number has been correctly written so that the cross totalizer registers zero on every dial, lever 108 is forced by 100 nose 100 to the position shown in Fig. 3 100 while the latchlever remains in its normal position and continues to prevent movement of lever 74 by spring 84, so that the locking mechanism is not thus affected. The cross totalizer, released as totalizer 1 approaches 105 the sub-units position and drawn to the right by spring 19, carries lever 108 from nose 100 whereupon lever 108 is restored to its normal position by spring 113. Instantly 110 thereafter the operator may replace the finished ledger sheet with another and continue his work. As soon as latch 69 is released by the withdrawal of cam plate 2 from underneath roller 63, spring 72 turns the latch until pin 79 is forced against edge 81 of 115 projection 82 as before explained and as shown by Fig. 4.

It will be noted that the feeler comb will be normally held away from the pinions 102, by the light spring 113, so that said 120 comb does not touch said pinions when the latter are turning; and that said comb is pressed against said pinions as shown in Fig. 4, after all of the wheels have been turned to zero, this being done by the power 125 of the much stiffer spring 98. If some dial is not at zero, the comb cannot rock forward, and spring 98 is stretched, and actuating lever 74 is released to operate the lock. The feeler-comb is pressed toward the pinion 130

only momentarily at the time when a clearance test is required. The comb is so pressed against the wheels every time the cross totalizer moves from units towards sub-units 5 position, and the latchlever 90, 91 may be tripped several times in the course of one program; but at all of these times except the one following the writing of the new balance, the lever 74 is restrained by the latch 10 69 and the lock is therefore not operated.

If the operator does not correctly copy the new balance, so that not every dial of the cross totalizer registers zero, lever 108 cannot be turned to the position shown in Fig. 15 3 for at least one of the feeler fingers acts on a long tooth of the pinion in front of it as soon as lever 108 starts to turn, and then end 119 of the lever cannot be depressed as it can be when the cross totalizer is clear.

20 But with the denominational stepping movement of the cross totalizer towards sub-units position, from units position, end 119 of lever 108 acting against nose 100 of the latchlever turns the latchlever so that lug 95 is 25 swung downward and away from edge 97 of projection 82 (Fig. 2), whereupon lever 74 is turned by spring 84 to the position shown in Fig. 2. Simultaneously the upper end of lever 28 is forced against frame plate 30 6 by the action on this lever of lug 86 at the lower end of arm 78 of lever 74. Lever 28 is held by lever 74 in contact with plate 6 until the latter lever is moved by hand from the position shown in Fig. 2. While lever 35 28 is so held, plate 34 of the above described locking mechanism is in its lowest position, and the operator could not work any of the computing mechanism of the machine for should he attempt to do so any vertical to- 40 talizer or dummy standing over the main master wheel would keep the lower end of plate 34 in front of slot 37 in stud 36 so that arm 48 could not swing backward into the slot and universal bar 46 could not be ac- 45 tuated and a numeral key could not be depressed. Hence, he would be notified that he had made an error. He can unlock the machine instantly to enable the error to be corrected by pushing finger piece 87 to- 50 wards frame plate 6 until lever 74 reaches its normal position. As he does this spring 98 restores the latchlever 90, 91 to its normal position so that lug 95 again crosses edge 97 of projection 82 and will hold lever 74 as 55 shown in Fig. 1, where it does not affect the ordinary action of lever 28 for the purposes explained in said Wahl patent. After the operator has unlocked the machine he is able to correct the error in a well known 60 manner and then continue his work.

As cross totalizer 20 is drawn towards sub-units position, from units position, by a vertical totalizer or dummy not having a tripper 2, lever 28 is not forced against frame 65 plate 6 by lever 74, although if the cross

totalizer is not clear the latchlever is rocked by the action of its nose 100 on the top 119 of lever 108. Latch 69 acting on lever 74 then prevents that lever from actuating lever 28. The latchlever is restored to its 70 working position by spring 98 as soon as the top 119 of lever 108 is carried away from the nose of the latchlever by the cross totalizer in jumping to the right. Although latch 69 is rocked whenever totalizer 1 is 75 drawn from the left to the right side of the main master wheel, yet latchlever 90, 91 then prevents lever 74 from actuating lever 28.

If, as is sometimes the case, the dials of the 80 cross totalizer are not exactly aligned when the totalizer is cleared, they are brought to true alignment by force transmitted to them from spring 98 through the latchlever 90, 91, the lever 108 and the feeler fingers 107 85 and pinions 102. When lever 108 is actuated at the end of a clearing operation, each feeler finger is pushed against the long teeth adjacent to the short tooth of the pinion and thus exerts an aligning action, as will be 90 understood. When a clearing operation is performed, the feeling device or feeler is rocked to the position shown in Fig. 4 if the operation is successful, or the locking mechanism is actuated if the operation is not suc- 95 cessful; and it will be noted that this operation of the clearance proving mechanism takes place while the cross totalizer steps from units position towards sub-units position, instead of during the jump of the cross 100 totalizer to the right. In other words, this clearance proving mechanism completes its work before the cross totalizer starts to jump. Consequently if the very narrowest vertical totalizer or dummy ever used is set 105 close to and on the right side of totalizer 1, it does not prevent the action of this clearance proving mechanism, although the cross totalizer may not jump more than three or four letter space distances on its release from 110 totalizer 1, before hook 22 is arrested by the lug 25 on the right side plate of the narrow totalizer or dummy. In short, it makes no difference in the use of my clearance proving mechanism whether the totalizer employed 115 be broad or narrow.

It is believed to be apparent from the foregoing description that lever 74 is a normally restrained actuating device by which lever 28, included in the locking mechanism, is forced to its working position when the lever 74 or actuating device is released, that this actuating device is held inactive in all operations of the machine except clearance proving operations, and that it is so held in 120 every clearance proving operation when the totalizer stands in and starts to step from unit's position, by arm 90 of the latchlever and by nothing else, as then latch 69 is in 125 the position shown in Fig. 1. 130

It will be understood that the above described program is but one of many which might have been taken to illustrate the utility of this invention and that much work such as is commonly done when various other programs are followed can be facilitated by its use.

What I claim as new and desire to secure by Letters Patent, is:—

- 10 1. In a calculating machine, the combination with register wheels arranged in a denominational series, mechanism that includes a stepping carriage and that as the carriage steps connects those wheels successively 13 with a common actuator, and a feeler that is required to act on the wheels and that is normally held clear of them, of feeler actuating means including a device mounted on the 20 carriage and a device mounted on the framework and held in the path of travel of the other device at and only at a place which the latter reaches in a stepping movement of the carriage after the common actuator has 25 engaged the register wheels above the units wheel.
2. In a calculating machine, the combination with a stepping totalizer that as it steps carries the wheels of a denominational series contained in it successively across and into 30 and from engagement with a common actuator, and a feeler contained in the totalizer and required to act on the wheels and normally held clear of them, of feeler actuating means including a device mounted on the 35 totalizer and a device mounted on the framework and held in the path of travel of the other device at and only at a place which the latter reaches in a stepping movement of the totalizer after the common actuator 40 has engaged the wheels of said series that are above the units wheel.
3. In a calculating machine, the combination with register wheels arranged in a denominational series, mechanism that includes 45 a stepping carriage and that as the carriage steps connects those wheels successively with a common actuator, and a feeler that is required to act on the wheels and that is normally held clear of them, of feeler actuating means including a device mounted on the 50 carriage and a device mounted on the framework and held in the path of travel of the other device at and only at a place which the latter reaches in a stepping movement of the 55 carriage after the common actuator has engaged the register wheels above the units wheel, one of these devices being movable from its normal position by the other when the 60 wheels are not clear and being immovable by the action on it of the other when the wheels are clear.
4. In a calculating machine, the combination with a stepping totalizer that as it steps carries the wheels of a denominational series 65 contained in it successively across and into and from engagement with a common actuator, and a feeler contained in the totalizer and required to act on the wheels and normally held clear of them, of feeler actuating means including a device mounted on the 70 totalizer and a device mounted on the framework and held in the path of travel of the other device at and only at a place which the latter reaches in a stepping movement of the totalizer after the common actuator has 75 engaged the wheels of said series that are above the units wheel, the device on the framework being movable from its normal position by the other when the totalizer is not clear and being immovable by the action on it of the other when the totalizer is clear.
5. In a calculating machine, the combination with a stepping totalizer that as it steps carries the wheels of a denominational series contained in it successively across and into 80 and from engagement with a common actuator, and a feeler contained in the totalizer and required to act on the wheels and normally held clear of them, of feeler-actuating means including a lever mounted in the 85 totalizer and connected to the feeler and extending through the top of the totalizer casting, above which its upper end is normally held at the limit of its upward movement, a spring acting on the connected lever and 90 feeler and tending to keep them both in their normal positions, a movable device mounted on the framework and held in the path of travel of the upper end of the lever at and only at a place which that end of the lever reaches in a stepping movement of the 95 totalizer after the common actuator has engaged the wheels of said series that are above the units wheel, and a retaining and restoring spring connected to said device, this 100 spring being strong enough to prevent movement of said device by said lever when the totalizer is clear but not strong enough to prevent such movement when the totalizer 105 is not clear.
6. In a calculating machine, the combination with a stepping and jumping totalizer that as it steps carries the wheels of a denominational series contained in it successively across a common actuator and that 110 thereafter ends its stepping travel and jumps back, and a feeler contained in the totalizer and required to act on the wheels and normally held clear of them, of feeler actuating means including a device mounted on the 115 totalizer and a device mounted on the framework and projecting into the path of travel of the other device only at a place which the traveling device reaches when the totalizer is near the end of its stepping movement and from which the traveling device recedes instantly after the totalizer 120 starts to jump back.
7. In a calculating machine, the combination with a stepping totalizer that as it 125

steps carries the wheels of a denomination totalizer contained in it successively across and into and from engagement with a common actuator, a feeler contained in the totalizer, and locking mechanism, of a device mounted in and projecting from the totalizer and connected to the feeler, a latchlever that is mounted on the framework and that is tripped by said device as the totalizer 70 steps from units position when the totalizer is not clear, and an actuating device that is held inactive by the latchlever at the start of the step and that imparts motion to a portion of the locking mechanism when the latchlever is tripped in that step.

8. In a calculating machine, the combination of a stepping totalizer that as it steps carries the wheels of a denominational series contained in it successively across and into and from engagement with a common actuator, a feeler contained in the totalizer and required to act on the wheels and normally held clear of them, and locking mechanism, of a lever mounted in the totalizer and connected to the feeler and extending through the top of the totalizer casing above which its upper end is normally held at the limit of its upward movement, a spring acting on the connected lever and feeler and tending to keep them both in their normal positions, a latchlever that is mounted on the framework and that is tripped by the upper end of the traveling lever as the totalizer steps from units position when the totalizer is not clear, and that depresses the upper end of the traveling lever as the totalizer steps from that position when it is clear, and an actuating device that is mounted on the framework and held inactive by the latchlever when the totalizer is in units position and that imparts motion to a portion of the locking mechanism if the latchlever is tripped and continues to be held inactive by the latchlever if the latter is not tripped.

9. In a calculating machine, the combination with a main actuator, a main decimal truck that steps to each denominational position, a totalizer casing mounted thereon, a cross truck that is picked up by said casing as it steps and approaches the main actuator and that is released from the casing and jumps back as the carriage steps from units position, a cross totalizer attached to the cross truck, a feeler contained in the cross totalizer, and locking mechanism, of a device mounted on and projecting from the cross totalizer and connected to the feeler, a latchlever that is mounted on the framework and that is tripped by said device as the cross totalizer steps from units position when it is not clear, an actuating device that is mounted on the framework and normally held inactive by the latchlever and that imparts motion to a portion of the locking mechanism when the latch-

lever is so tripped, a latch mounted on the framework and normally acting on said actuating device, releasing mechanism which is mounted on the framework and connected to the latch and by which the latch is movable to an inactive position, and a trippet attached to the said casing and arranged to act on said releasing mechanism when the carriage stands in units position.

10. In a calculating machine, the combination with a stepping totalizer that as it steps carries the wheels of the denominational series contained in it successively across a common actuator, a feeler contained in the totalizer, and locking mechanism, of a normally restrained actuating device by which a portion of the locking mechanism is forced to its working position when this actuating device is released, a restraining latch that acts on said actuating device in clearance proving operations when the totalizer is in units position, and latch tripping means that includes the feeler and that is forced by the totalizer in its next step to trip the latch in case the totalizer is not clear.

11. In a calculating machine, the combination with a stepping totalizer that as it steps carries the wheels of a denominational series contained in it successively across a common actuator, a feeler contained in the totalizer, and locking mechanism, of an actuating device which is pivoted on the framework and normally held inactive and by which a portion of the locking mechanism is forced to its working position when this actuating device is released, and releasing means that includes the feeler and other devices that are forced by the totalizer to coact in the last step of a clearance proving operation when the totalizer is not clear, this releasing means including part of the means that holds the actuating device normally inactive.

12. In a calculating machine, the combination with a stepping totalizer that as it steps carries the wheels of a denomination series contained in it successively across a common actuator, a feeler contained in the totalizer, and locking mechanism including a lever, of an actuating device that is pivoted on the framework and normally held inactive and that is effective when it is released to force said lever of the locking mechanism to its working position, a latchlever that is mounted on the framework and acts at one end on said actuating device in clearance proving operations when the totalizer is in units position and that has a nose at its other end, one arm of this latchlever being part of the means by which the actuating device is normally held inactive, and a device that is mounted in the totalizer and connected to the feeler and has an arm projecting from the casing, the nose of

the latchlever being normally in the path of travel of the outer end of this arm and in that portion of the path over which that end of the arm travels when the totalizer 5 steps from units position.

13. In a calculating machine, the combination with a stepping totalizer that as it steps carries the wheels of a denominational series contained in it successively across a 10 common actuator, a feeler contained in the totalizer, and locking mechanism, of an actuating device which is held inactive in all operations of the machine except clearance proving operations and by which a portion 15 of the locking mechanism is forced to its working position when this actuating device is released, and releasing means that includes the feeler and other devices that are forced by the totalizer to coact in the last 20 step of a clearance proving operation when the totalizer is not clear.

14. In a calculating machine, the combination with a stepping totalizer that as it steps carries the wheels of a denominational 25 series contained in it successively across a common actuator, a feeler contained in the totalizer, and locking mechanism, of an actuating device which is held inactive in all operations of the machine except clearance 30 proving operations and by which a portion of the locking mechanism is forced to its working position when this actuating device is released, two holding devices that sometimes act together and each of which sometimes acts alone on the actuating device, releasing means that 35 disables one of the holding devices before the totalizer steps to and from units position, and releasing means that includes the feeler and that disables the 40 other holding device as the totalizer steps from that position, if it is not clear.

15. In a calculating machine, the combination with a main decimal truck that steps to each denominational position, a totalizer 45 casing mounted thereon, a cross truck that is picked up by said casing as it steps and

approaches the main actuator and that is released from the casing and jumps back as the carriage steps from units position, a cross totalizer attached to the cross truck, 50 a feeler contained in the cross totalizer, and locking mechanism, of an actuating device which is held inactive in all operations of the machine except clearance proving operations and by which a portion of the locking 55 mechanism is forced to its working position when the actuating device is released, two holding devices that sometimes act together and each of which sometimes acts alone on the actuating device, releasing means in 60 which a trippet attached to said casing is included and by which one of the holding devices is disabled, and releasing means that includes the feeler and that disables the other holding device as the cross totalizer 65 steps from units position when it is not clear.

16. In a calculating machine, the combination with a stepping totalizer that as it steps carries the wheels of a denominational 70 series contained in it successively across a common actuator, a feeler contained in the totalizer, and locking mechanism, of an actuating device pivotally mounted on the framework, holding means by which the actuating device is held normally inactive and in which is included a latchlever that is pivotally mounted on the framework, and releasing means that includes the feeler and a device that is mounted in the totalizer 75 and acts on the latchlever, a portion of the locking mechanism being close to the actuating device and movable to its working position by that device.

Signed at Ilion, in the county of Herkimer and State of New York, this 19th day of December, A. D. 1922.
